MACHINE FOR APPLYING AN INTERMEDIATE STRIP AND BASE TO PILE FABRICS

Harold H. Baynton and James William Foster,
Freehold, N. J., assignors to A. & M. Karagheusian, Inc., New York, N. Y., a corporation
of Delaware

Application July 2, 1935, Serial No. 29,546

8 Claims. (Cl. 154—1)

Our invention relates to new and useful improvements in a machine for the manufacture of rugs, and more particularly to a machine for applying either a layer of fabric (burlap) over

5 the rear surface of the pile fabric to act as a base or applying this fabric and also a felt base and simultaneously cementing the pile fabric, intermediate layer, and the base into substantially one integral structure.

10 Another object of the invention is to provide a machine to which a strip of pile fabric is fed while, at the same time, there is passed through the machine a further fabric (burlap) that is cemented to the pile fabric, this fabric acting 10
15 as a back, as will be explained. The pile fabric may then be stored and sold in this condition or it may later be run through the same machine and a further felt back cemented thereto.

Still another object of the invention is to provide a machine through which a strip of pile fabric is fed, while simultaneously there is added a further fabric strip (burlap) and a felt base, the several parts being cemented to form an integral structure on the one course through the machine.

25 Still another object of the invention is to provide a machine, wherein a pile fabric with outstanding integral marginal strips (which are not tufted) may be passed through the machine, the machine, in turn, automatically turning over these marginal strips and cementing them to the pile fabric. Also, during the course of the pile fabric through the machine, a further strip of fabric is cemented in place and a felt back 30
35 added, if desired.

Still another object of the invention is to provide a simple and inexpensive machine, wherein a roll of pile fabric, a roll of burlap, and a roll of felt are automatically passed through the machine, the roll of pile fabric first having its marginal side strips coated with a cementitious rubber. Then as the fabric continues through the machine, these marginal side strips will be folded back on the fabric and cemented in position. 40
45 The roll of burlap is then applied to the back of the pile fabric, cemented in position and, at the same time, a layer of felt is applied, so that the pile fabric now, when delivered from the machine, will be in the form of a completed strip 50
55 to be made up into rugs or carpets.

Still another object of the invention is to provide a machine through which is fed the pile fabric, burlap and felt, the machine automatically folding and cementing the side marginal edges of the pile fabric, impregnating an inter-

mediate layer of burlap with rubber in liquid form, and cementing the same and a felt back to the strip all during the one course through the machine.

Still another object of the invention is to provide a simple form of machine, wherein the pile fabric is fed from a roll at one side of the machine, passed over rollers so that the protruding marginal side edges may be gummed, and folded back on the pile fabric, after which a strip of burlap, which in turn has passed either over or under a roller, depending on whether both sides are to be coated, with a strip of felt are passed between rollers, together with the pile fabric, so that the several parts may be tightly pressed and cemented. The strip is then mechanically fed from the machine and mechanically fed onto a roller and stored until desired.

Still another object of the invention is to provide a relatively simple machine that will fold and cement the protruding marginal edges of a strip of tufted fabric and then cement either one layer of burlap or a layer of burlap and felt and then wind the completed strip on a roll at the end of the machine.

Still another object of the invention is to provide a simple machine for attaching a burlap strip and a felt base to a pile fabric, the article itself forming the subject-matter of an application filed by us on June 4, 1935, bearing Serial Number 24,940, for Rugs and carpets.

Still another object of the invention is to provide a machine for especially attaching an intermediate strip or base to a pile fabric, the pile fabric, in turn, being made on a loom which forms the subject-matter of a separate application about to be filed by us in the United States Patent Office.

With these and other objects in view, the invention consists in certain new and novel features and combination of parts, as will be hereinafter more fully explained and pointed out in the claims.

Referring now to the drawings showing a preferred embodiment,

Fig. 1 is a side elevation of the machine, the dotted lines following the course of the burlap from one of its rolls, showing how the burlap may be by-passed over the roller instead of under the roller if the felt base is not to be added, the dotted line of the felt showing its course if it is to be later added;

Fig. 2 is a top plan view of the machine;

Fig. 3 is a fragmentary view of the pile fabric

with its marginal edges being turned back as it passes through the folder;

Fig. 4 is a perspective of the rollers for applying rubber in liquid form to the marginal side strips of the pile fabric;

Fig. 5 is a perspective of the pile fabric, showing one of the marginal edges as gummed before being folded back;

Fig. 6 is a perspective of the pile fabric with the intermediate layer and base lifted back for the sake of clearness of illustration;

Fig. 7 shows the completed strip before the pile is trimmed;

Fig. 8 shows the completed strip in its normal position and the pile having been trimmed;

Fig. 9 is a fragmentary section showing how adjacent strips may be placed prior to sewing;

Fig. 10 shows adjacent strips as having been sewed to each other.

At the outset, it might be mentioned that the loom or tufting machine on which the pile fabric is made forms the subject-matter of a separate application filed by us on July 18, 1935, bearing Serial Number 32,098, for Machine for manufacturing pile fabric.

Likewise, the article (completed strips) also forms the subject-matter of a separate application filed by us on June 4, 1935, bearing Serial Number 24,840, for Rugs and carpets.

Referring now more particularly to the several views, and for the moment to Fig. 1, there is shown a metal framework 1, which framework may be made up of angle iron and the parts riveted or bolted together. There may also be seen the top side bars 2 comprising a part of the frame and the upright posts 3 on each side of the machine and positioned a little to one side of the center of the frame. On the base of the frame and toward the rear may be seen a motor 4, which drives a reduction gearing 5, from which extends the two sprocket chains 6 and 7. The chain 6, in turn, drives a shaft 8, which is mounted on the uprights 3 of the frame, the shaft 8, in turn, being provided with the roller 10, in which roller there are mounted a plurality of spikes or pins 11, so that they may engage the completed material 55 which, in turn, passes over this roller and thus draws the same through the machine.

In a like manner, the chain 7 operates through the sprocket 12, which is mounted on the shaft 14. On the shaft 14 is a further sprocket 15 which, in turn, operates the chain 16, this chain, in turn, passing over a sprocket 17 on the shaft 18. On the shaft 18, there is a roller 19 with the pins 20.

The shaft 18 is, in turn, mounted on bracket arms 21, which bracket arms are loosely mounted at their lower end on the aforementioned shaft 14, so that as the fabric builds up into a roll 22, the roller 19 with its pins may move rearwardly to thus compensate for the ever increasing size of the roll. A spring 23 is shown as fastened to a bracket arm 21 and to the frame 24, on which frame 24 the aforementioned carpet roll 22 will be built. There is a shaft 25 for this roll mounted in the hangers 26 of the aforementioned base or stand 24. Thus, it will be seen that the motor through the reduction gear and chains heretofore mentioned will pull the pile fabric through the machine and also wind it at the same rate on the roll at the rear of the machine.

While referring to this rear portion of the machine, there will also be noticed the roller 27 ex-

tending across the machine and elevated slightly with respect to the lower edge of the roller 19. In a like manner, there is a roller 28 mounted on the upper portion of the frame and above the roller 19, so that the strip of pile fabric, as will be explained, will pass over the roller 28 about the roller 19 and up over the roller 27 as it passes to the final roll 22.

Now still glancing at Figs. 1 and 2 for the moment, there will be seen the two small width 10 rollers extending between the side uprights 3. Viewing these from the top (Fig. 2), there will be seen a metal shaft 29, on which shaft 29 are the two aforementioned rollers 28, these being mounted on the respective ends of the shaft. The shaft 29, in turn, is mounted in the oppositely spaced arms 30, which arms are pivotally mounted, as at 31, to the brackets 32 fastened to the uprights 3. The arms 30 have the grooves 33 therein, so that weights 34 may be supported from these arms and the amount of pressure exerted by the shaft 29 and its rollers 28 may be lessened or made greater, as desired, by moving the weight on the arms 30.

Directly below the shaft 29, there is a roller 35, which is mounted on the shaft 36, the opposite ends of the shaft being provided with the small rollers or collars 37 which, in turn, receive the weight transmitted through the arms 30 and the shaft 29. The shaft 36 has the blocks 38 on its opposite ends with the grooves 39 therein, into which fit the guides 40, so that this shaft 36 may move in a vertical direction.

Rigidly mounted on the top bars 2 and beneath the aforementioned roller is another roller 41, its shaft 42 being mounted in the bearings 43.

As far as the specification has proceeded, it will be seen that the pressure between the roller 41 and the roller 35 may be lessened or made greater, as desired, so that the requisite amount of pressure may be applied to the burlap, felt, and pile fabric, as they pass through these rollers, which will be shortly described.

Glancing for the moment to the forward portion of the machine, that is, the portion to the left of Figs. 1 and 2, there may be seen a trough 44 (a part of the end plate being broken away at 45, Fig. 1, for the sake of clearness of illustration), and in this end plate and on the other end plate 44 at the opposite side of the machine, there will be mounted a roller 46, which roller has the central shaft 47.

Located above the trough and to the left thereof, Fig. 1, may be seen an idler or guide roller 48, and likewise mounted on the machine along the rear edge of the trough may be seen the roller 49, which latter roller 49 being adjacent the aforementioned roller 46.

Still glancing at Fig. 1 for the moment, there will be noticed below the trough 44 another similar but somewhat smaller trough 50 supported by cross bars 51. Likewise mounted in these cross bars and in the trough is a shaft 52, which is provided on its opposite ends with rollers 53 (see Fig. 4) which are relatively narrow in width. In fact, the width of these rollers is the same as the width of the marginal edges 54 (see Fig. 5) of the pile fabric 55. The stitches are on rows, as at 56, and it will be understood, of course, that these stitches go completely across the pile fabric. These stitches form loops which are afterwards cut by the pile cutter, as will be understood.

Referring again to Fig. 1, and glancing for the moment to the left thereof, there may be seen a guide roller 57, while to the rear of the trough and 75

in line with the roller 57 is another roller 58. Likewise, in line with the trough 50, and to the left thereof in Fig. 1, there is another guide roller 59, and to the right thereof is the roller 60, so that the pile fabric when entering the machine may pass over and under these rollers, as will be shortly mentioned.

Located between the rollers 59 and 60, there is mounted, as at 61, a folder 62, which is formed of metal, in the usual manner, having the bottom 63 and the flaring and folded-back wings 64, so that when the strip of pile fabric 55 (Fig. 3) passes through this folder, the marginal edges 54 will be folded back on the pile fabric. The shaft 52 with its rollers 53 mounted in the trough 50, which is filled with a rubber cement, will apply the cement to the marginal edges 54, and the folder 62 will turn back these edges, which will afterwards be compressed by the rollers 41 and 35.

Now mounted in front of the machine is a support 65 having the bearings 66, in which the roller 67 will be mounted and on which has been wound the pile fabric 55. Suitably mounted above the machine in a hanger 68 will be mounted a roll of burlap 69 and a roll of felt 70, so that a burlap strip 69 may be impregnated and cemented to the pile fabric 55 and so that simultaneously there may also be applied to the pile fabric a felt base 70.

Before tracing the course of the several strips of material through the machine, it might be stated that if just the burlap is to be cemented to the pile fabric 55, then it is only necessary that the burlap be coated on its one face with the cementitious rubber, and in that instance, the burlap 69 will take the path shown by the dotted lines, and pass under the roller 48 and then be by-passed up over the roller 46 and then under the roller 49, whereas if the felt backing is to be applied at the same time, then the burlap strip 69 (which will now act as an intermediate layer) must be coated on both its sides, and in this instance, instead of passing it over the roller 46, it will be fed down past the roller 48 and under the roller 46 and then under the roller 49.

In Fig. 1, there will be noticed right below the roller 49 a small scraper 71, between which the strip will pass, so that any superfluity of rubber cement may be scraped from the burlap before it is cemented under pressure to the pile fabric. Likewise, in the lower trough that cements the marginal side strips may be seen a further scraper 72.

Referring for the moment to Figs. 5 to 10, inclusive, there will be seen, as heretofore mentioned, the pile fabric 55 with the stitches 56 to form the pile 56', while in Fig. 6, there is shown the marginal edges 54 turned back on the pile fabric and cemented thereto. Likewise, there is shown the intermediate strip of burlap 69 with its cementitious coating of rubber thereon, the burlap being rolled back for the sake of clearness. There may also be seen the felt base 70, which may be of any desired make, but preferably a felt with the pockets pressed therein and known to the trade as "Ozite".

In Fig. 7, there is shown the completed rug or carpet strip, the pile 56', however, not being trimmed, whereas in Fig. 8, the pile fabric has been trimmed by regular rotating blades (not shown).

As set out in the companion application on the article, shown and described in the application filed by us on June 4, 1935, bearing Serial Number 75 24,940, for Rugs and carpets, by turning back

these marginal edges 54 and still leaving a slight projection of the edge, which is not tufted, a number of strips of the finished material can be sewed, as at 73, so that the seam will not show through the pile.

We have found that the best cement to be used in cementing the marginal edges, the intermediate strip, and the felt back is known in the trade as "Statite", it being a rubber cement in liquid form, which changes from liquid to elastic form when exposed to the air. Thus, by impregnating the intermediate strip 69 with this rubber, not only are all of the stitches held in their places, but there is an elasticity and softness to the rug or carpet that is not otherwise possible. Again, by impregnating the burlap strip 69 with a rubber cement, there is a firmness and rigidity given to the article that would not otherwise be present, and the rug or carpet will lie flat on the floor and will not give or wrinkle from footsteps.

Now briefly tracing the movement of the pile fabric 55 through the machine, it will pass from its roll under the roller 57, around the roller 58, and the marginal side edges 54 will contact with the rollers 53, which are mounted in the trough 50 and thereby apply this rubber cement to the marginal edges. As the fabric travels through the machine, it will next pass over the roller 59 and back through the folder 62, so that the edges will be folded back on the pile fabric, as may be seen from Fig. 3. The pile fabric then passes upwardly and over the roller 41. Here, it combines with the strip of burlap 69 that is passed under the roller 46, through the trough 44, and under the roller 49, where these two fabrics are then subjected to a heavy pressure in passing through the weighted roller 35 and its complementary roller 41. However, before passing through the last-mentioned rollers, it will be seen that the strip of felt 70 has also passed downwardly under a roller 74 to meet the pile fabric and burlap, so that it, too, will be subjected with the other strips to the pressure of these two rollers 35 and 41 to thereby tightly compress the several strips to each other, the intermediate strip, it being remembered, being still wet from its passage through the liquid rubber in the trough 44.

After the material passes under the two aforementioned rollers, they will move rearwardly over the roller 28 and about the spike roller 10, this spike roller drawing the pile fabric, the burlap, and the felt (which it is remembered are now united in the one strip) through the machine.

The finished strip then continues to be wound in a roll 22, and this roll is actuated by the spike roller 19, both of these being driven from the aforementioned reduction gear 5 which, in turn, is actuated by the motor 4.

It may not always be desirable to apply the felt base 70, and in this instance, the burlap strip 69 really becomes the backing or base. As heretofore mentioned, it will then only be necessary to coat the burlap 69 on its one face. To do this, the burlap strip is run under the roller 48 and over the cementing roller 46, rather than through the trough, and then through the machine in the ordinary way.

If, at any time, it is desirable to apply the felt base, the felt would be led under the roller 48, rather than directly under the roller 74, then over the roller 46, and then in through the pressure rollers and firmly cemented to the fabric strip and the pile fabric, in the manner aforementioned.

From the foregoing, it will be seen that we have

provided a machine for gumming the outer marginal edges of a pile fabric and then turning these edges back on the pile fabric. As the pile fabric continues to pass through the machine, 5 the strip of fabric is impregnated with a rubber cement and securely cemented under pressure to the pile fabric. Also, a felt base may be applied at the same time or may be applied at a later date, if desired.

10 We have found that the machine, as designed, is very efficient in service and permits of a great amount of yardage of carpet strips or rug strips being completed in a day's run.

Many slight changes are possible in the construction hereinbefore set forth without in any manner departing from the spirit of the invention.

Having thus described our invention, what we claim as new and desire to secure by Letters 20 Patent is:—

1. A machine for applying a fabric strip and felt backing to a pile fabric including means for gumming the marginal strips of the pile fabric and turning the said strips back on the pile fabric, 25 means for impregnating a fabric strip with a cement in liquid form, means for feeding a felt base to the pile fabric and said strip and pressing the several layers together, means for pulling the said completed strip through the machine,

30 and means for winding the completed strip on a roll.

2. A machine for applying a fabric strip and felt backing to a pile fabric including means for gumming the marginal sides of the pile fabric, 35 means for folding back the gummed marginal sides, a trough for holding a liquid rubber cement, means for directing a fabric strip through said trough, means for applying a felt base to the impregnated fabric strip, means for simultaneously pressing the pile fabric, strip and felt base together whereby the impregnated strip will tightly cement the pile fabric, strip and base into substantially a unitary carpet strip, and means for pulling the completed strip through the 45 machine.

3. A machine for applying an intermediate strip and a felt backing to a pile fabric including means for gumming the marginal strips of the pile fabric and turning the said strips back on 50 the pile fabric, means for impregnating a fabric strip on its under and upper surfaces with a rubber cement in liquid form, means for simultaneously feeding a felt base to the pile fabric and the strip, roller means for subjecting the completed strip to a predetermined amount of pressure to thus cement the several fabrics and the felt base into a substantially unitary structure, means for drawing the completed strip through the machine, and simultaneous means for winding the 55 strip on a roll.

4. A machine for impregnating with a rubber cement a fabric strip and a felt base to a pile fabric, said fabric having marginal side edges that are not tufted, said machine including means 60 for gumming and holding the said marginal strips back on the pile fabric, means for directing a fabric strip through a liquid cement, means

for feeding a felt base through the liquid cement while the same is still soft, rollers through which the pile fabric, strip, and felt base are passed, means for drawing the completed strip through the rollers, and means for winding the completed strip on a roll and at the same speed that the strip is pulled through the machine. 5

5. A machine for turning back the non-tufted marginal side edges of a pile fabric and applying an intermediate impregnated fabric and adding 10 a felt base including a framework, pressure rollers mounted in said framework, means for varying the pressure between the rollers, means for running the marginal side strips of the fabric over a cement applying roller, a folder for turning back the said side edges as the pile fabric passes through said folder, a trough, a roller therein for applying cement to a fabric strip, means for directing the pile fabric strip and a felt base to said pressure rollers, means drawing 20 the strip of pile fabric, fabric strip, and felt base through said pressure rollers, and means for rolling up the said strip after passing from the machine.

6. A machine for gumming and folding the 25 selvedge of a pile fabric and applying an intermediate strip and felt base including means for applying cement to the said selvedge, means for folding back the selvedge, means for impregnating a fabric on both its surfaces and feeding 30 the said strip to the pile fabric in front of pressure rollers, means for supplying a felt strip to said fabrics in front of pressure rollers, pressure rollers, and means for pulling said cemented parts in the form of a strip through the machine and 35 winding the same on a storage roll.

7. A machine for gumming and folding back the marginal side edges of a pile fabric and cementing and applying a fabric backing including a framework, a roller and liquid cement supply 40 over which the marginal edges of the pile fabric are passed, a folder through which said fabric also passes, the said folder turning back the gummed marginal side edges of the fabric, a further tank for liquid cement and a roller therein, 45 means for passing the pile fabric in contact with and over the top of said roller, pressure rollers, means for threading the pile fabric and the fabric strip through said rollers, and power-driven means for pulling the pressed pile fabric and 50 fabric strip through said rollers and delivering the same from the machine.

8. A machine for applying a liquid-coated fabric strip to a pile fabric and gumming and turning the marginal side edges of the fabric including 55 means for gumming the said marginal side edges, means for folding back the side edges, means for applying a cement to the under surface of a fabric strip to act as a backing for the pile fabric, pressure rollers, means for regulating the pressure between said rollers, roller means for guiding the two fabrics to the pressure rollers, and means for pulling the said fabrics through said rollers and delivering the same from the said machine. 60

HAROLD H. BAYNTON.
JAMES WILLIAM FOSTER.
